UNITED STATES PATENT OFFICE.

EDWIN N. WEAVER, OF JERSEY CITY, NEW JERSEY.

COAL-HANDLING MACHINE.

1,351,593.

Specification of Letters Patent. Patented Aug. 31, 1920.

Application filed May 24, 1919. Serial No. 299,596.

To all whom it may concern:

Be it known that I, EDWIN N. WEAVER, a citizen of the United States, and a resident of Jersey City, in the county of Hudson 5 and State of New Jersey, have invented a new and Improved Coal-Handling Machine, of which the following is a full, clear, and exact description.

This invention relates to coal handling machinery and has particular reference to power operated means for crushing and sizing lump material such as coal and having means for conveying the same from the crushing and sizing mechanism to an elevator which serves to deliver the material into an automatic weighing and registering device whence it is dumped into the lower end or boot of an upright conveyer tower from the top of which it is finally delivered 20 through a chute into the bunker hatch of a ship, barge, railway car, or other means of conveyance.

Among the objects of the invention is to provide means for rapidly handling, sizing, 25 and transferring bulk material such as lump coal in regulatable quantities from one ship or conveyance to another, as for example in the rapid coaling of ships or transports.

Another object of the invention is to provide a rapid and satisfactory means for transferring coal from a lighter, barge, or other vessel into a sea-going vessel or the like with the employment of practically all power operated machinery, thus dispensing with 35 the necessity for employing many labors, a fact greatly appreciated at times when labor is hard to secure and when the coaling of vessels must be performed in the least possible time.

With the foregoing and other objects in view the invention consists in the arrangement and combination of parts hereinafter described and claimed, and while the invention is not restricted to the exact details of 45 construction disclosed or suggested herein, still for the purpose of illustrating a practical embodiment thereof reference is had to the accompanying drawings in which like reference characters designate the same parts in the several views, and in which—

Figure 1 is a fragmentary plan view partly in section of a coal handling barge showing the principal parts of my invention.

Fig. 2 is a vertical longitudinal section of 55 the same.

Fig. 3 is a vertical transverse section on the line 3—3 of Fig. 2 and on a larger scale.

Fig. 4 is a vertical transverse section through the elevator tower and indicating the weighing device in elevation. 60

Fig. 5 is a plan view of the sizing plate and crusher actuator; and

Fig. 6 is a vertical transverse section of the elevator drum on the line 6—6 of Fig. 2.

Referring now more specifically to the drawings I show a barge or hull 10 of any suitable size, proportions, construction, or design but capable of self-support on the water and for carrying a considerable quantity of coal upon its hopper bottom 11. I 70 wish to state at this time once for all that by the term coal as employed herein I wish to be understood as covering generically any analogous lump or pulverulent material. The hopper is co-extensive with a considerable portion of the entire craft, room being reserved only for the operating machinery or the like. The ends of the carrying capacity consist of walls 12 and 13 adjacent to the ends of the barge, and in the end walls 12 75 and 13 are journaled longitudinal shafts 14 preferably parallel to each other and each fitted with a wheel 15 having a spiral flange or cam 16 formed on its curved surface.

The curves of the wheels on the same shaft 80 are so designed and fixed that all parts thereof in directions parallel to the shaft are equally distant. Furthermore, the wheels and the cams on one shaft are exactly the same as those on the other with the exception 85 that those on one shaft are to be presumed as having been turned through 180 degrees from the position of the other. These shafts 14 and the wheels fixed thereto are located beneath the inclined walls or sections of 90 said hopper bottom so that the coal carrying capacity of the craft is not materially affected thereby.

Extending longitudinally and centrally of the bottom of the barge and consequently 100 beneath the hopper bottom 11 is a conveyer shown as of the screw type and having a power shaft 17 to which is secured a spiral blade 18 movable in and along the trough 19 constituting the fixed wall of the conveyer and leading from one end of the hopper to the other. The shaft 17 is journaled in the walls 12 and 13 or in bearings 20 carried thereby. This shaft may be the primary power transmitting member to which 105 110

power is communicated from any suitable motor indicated as a reciprocating engine 21 at one end of the barge having a connecting rod 22 attached to a crank 23. To the shaft 17 are secured suitable transmission members such as sprocket gears 24 from each of which runs a sprocket chain 25 to and over a similar sprocket wheel 26 secured to the end of a shaft 14 above described.

10 Hence the shafts 14 and cam wheels thereon are driven simultaneously with and from the screw shaft 17 and all in the same direction. Thus it will be understood from Fig. 1 the cams of one pair of wheels 15 appear to be projected differently from those on the other side of the barge. In other words assuming the direction of rotation and movement of the parts as indicated by the arrows on Fig. 1 all of the cams or spiral blades 16 will be effective to throw the crusher actuator and sizing plate 27 in the same direction toward one end of the barge or the other.

Said plate 27 shown in detail in Fig. 5 comprises a central portion having a plurality of holes 28 extending from one end to the other which serve in the nature of a sieve or sifter when this portion of the plate is reciprocated to and fro endwise of the barge over the stationary sizing plate 29 having holes 30 lying just above the screw conveyer and with which the holes 28 are adapted to register at times. At each corner of the plate 27 which is essentially rectangular is provided an ear 31 having a notch 32 into which the adjacent cam flange 16 projects and has constant bearing in a direction radial with respect to the shaft 14. Between the field of the holes 28 and the side edges 40 of the plate 27 are provided on each side a rib 33 and a groove 34 both of which are straight but are flared with respect to each other from one end of the plate to the other, the groove having the greater flare with respect to the adjacent side edge of the plate, while the rib is slightly flared with respect to said edge but in the opposite direction. In other words while the plate as a whole is reciprocated to and fro endwise by the rotation of the shafts 14 and wheels connected thereto, devices having engagement with said ribs and grooves will be given reciprocation in the opposite direction or perpendicular to the movement of the plate 55 but with different degrees of throw or amplitude.

I provide two pairs of crushing jaws, one pair 35 having bars 36 along their remote edges having constant engagement in the grooves 34 and which consequently are given a considerable amount of lateral reciprocation toward and from each other in the bottom of the hopper for acting upon and reducing the largest lumps. The teeth 35' of these jaws are spaced somewhat farther

apart than the teeth 36' of the lower set of jaws whose remote edge portions or rails 37 have constant engagement with the ribs 33 and which consequently are given a transverse reciprocation toward and from each other a shorter distance than the reciprocations of the jaws 35. The purpose of these sets of jaws is to so reduce the lumps that they will all pass through the registering holes 28 and 30 as above set forth. Another function of these crushing jaws moreover is to facilitate the delivery of the coal from the hopper bottom to and through the conveyer even though no crushing of the lumps were necessary.

On the opposite side of the wall 13 from the hopper and directly against the wall is an elevator drum 38 of annular form and having a closed outer periphery and at least one wall 39 parallel to the wall 13. This drum, as shown best in Fig. 2, is antifrictionally supported by ball bearings at 40 and 41 for free rotation under the driving action of a sprocket chain 42 operating over a sprocket wheel 43 connected to one of the shafts 14 and extending around the outside of the drum and in engagement with the sprocket teeth 44 formed thereon. This drum is provided with a plurality of radially disposed partitions 45 subdividing the same into an annular series of buckets 46 which receive their charges of coal while passing beneath or along the delivery end of the conveyer trough 19. A guard wall 47 extends thence around and upward to a stationary chute 48 at the top portion of the drum and to and along which the coal is delivered from the buckets 46 as they come over the same in succession. The entire interior of the drum 38 is hollow and unobstructed.

The automatic weighing and registering devices comprise a box like device 49 having one end projecting well into the interior of the drum 38 and comprising side walls upon and between which is journaled on a horizontal axis 50 a rotatable weighing device having a plurality of blades 51 between each two of which is formed a pocket bounded by the side walls of the chamber 49 and by a vertical wall 52 spaced well forward from the elevator drum 38 and opposite the lower end of the chute 48. The rotation of the weighing device 51 is controlled by two sets of devices, first by a catch 53 comprising a finger projecting through the wall 52 into engagement with the point or edge of one of the blades 51 and which is released automatically when and only when the charge of coal received upon such blade between the chute 48 and the wall 52 is equal to a predetermined amount according to the adjusting or setting of a weight 53'. When the desired charge of coal is thus received the catch will be automatically released and the

weighing device is given a partial rotation until the next blade 51 is received upon and stopped by the catch 53. The other means for controlling the rotation of the rotatable device is a pawl and ratchet 51' coöperating with the shaft 50 which prevents any possibility of reverse rotation thereof. This catch device 53 may be adjusted with precision and will always act to deliver pre-determined quantities of coal at each actuation of the rotary device. A counter 54 is actuated to make a record of such fact so that at the end of a certain period of time the total number of weighed charges will be indicated.

When the loaded pocket 51 of the weighing device is to be dumped the coal therefrom will pass directly into the boot portion 55 of the bucket elevator which comprises a tower 56 having up and down legs on opposite sides of the weighing device and the chamber 49 and along which an endless series of buckets or flights 57 operate over and between a pair of head wheels 58 at the top of the tower, and with a sprocket wheel 59 connected to the axle 60 of said wheels. A sprocket chain 61 or its equivalent operates from a sprocket wheel 62 on one of the shafts 14 to and over the wheel 59 for operating the endless chain of buckets or flights and whereby the coal delivered into the boot 55 from the chamber 49 or weighing device pockets is picked up automatically and carried upward along the up leg of the tower 56 and dumped between the wheels 58 into a chute 63 the lower end of which may be adjustable in any direction to determine the point of delivery of the coal.

Thus it will be seen that from a single power plant located at any convenient place in or upon the craft I am able with a minimum amount of manual labor or attention to discharge quickly an entire load of coal, preparing it without hand pulverizing or crushing for the feeding of boilers or other furnaces and delivering it also in a weighed and quantity determined condition.

I claim:

1. In a coal machine the combination of a bottom, crushing means beneath the bottom serving to crush large lumps and facilitate the delivery of the material therefrom, a combined crusher actuator and sizing plate beneath the crushing means, means to reciprocate said actuator and plate, means between the crushing means and said actuator to cause the actuation of the crushing means in directions transverse to the direction of movement of the plate and actuator, and means to deliver the crushed coal after it passes through the sizing plate.

2. In a coal machine the combination of a bottom, a plurality of pairs of crushing jaws beneath said bottom, the jaws of each pair being movable toward and from each other, a crusher actuator beneath the jaws, and means to operate the actuator, connections between the actuator and the jaws to cause reciprocation of the jaws of one pair in directions opposite to that in which the other jaws reciprocate, the actuator being moved in directions perpendicular to the directions of the movement of the jaws.

3. In a machine of the class set forth, the combination of a horizontal plate provided along its longitudinal center with a series of sizing holes and having on opposite sides of the holes a pair of ribs extending lengthwise of the plate, but slightly divergent from each other and having on opposite sides of the ribs a pair of longitudinally extending grooves divergent from each other to a greater extent than the ribs and in the opposite direction, means coöperating with the plate to reciprocate it endwise, and two pairs of crushing jaws located above the plate and coöperating with the ribs and grooves respectively whereby the jaws of each pair will be reciprocated transversely of the plate toward and from each other as a result of the longitudinal reciprocation of the plate and to different distances due to the disparity of divergence of the ribs and grooves.

EDWIN N. WEAVER.
